BOOT

Salvatore C. Spinali, San Diego, Calif.

Application September 24, 1951, Serial No. 16,722

Term of patent 14 years

(Cl. D7—4)

To all whom it may concern:

Be it known that I, Salvatore C. Spinali, a citizen of the United States of America, residing at San Diego, in the county of San Diego and State of California, have invented a new, original, and ornamental Design for Boot, of which the following is a specification, reference being had to the accompanying drawings, forming a part thereof.

Fig. 1 is a top or plan view of a boot, showing my new design; Fig. 2 is a front elevational view thereof; and Fig. 3 is a side elevational view of the boot.

I claim:

The ornamental design for boot, substantially as shown.

SALVATORE C. SPINALI.
